MEANS FOR CHECKING THE SPEED OF REVOLVING DOORS

Filed Jan. 21, 1948

UNITED STATES PATENT OFFICE

2,565,581

MEANS FOR CHECKING THE SPEED OF
REVOLVING DOORS

John T. Unangst, Pittsburgh, Pa.

Application January 21, 1948, Serial No. 3,483

9 Claims. (Cl. 20—18)

1

This invention relates generally to revolving doors and particularly to means for intermittently checking the rotation thereof to prevent excessive speed and the possibility of injury resulting therefrom.

Revolving doors as now installed constitute a safety hazard to some extent because of the fact that some pedestrians are capable of exerting a greater physical force than others, coupled with the fact that doors vary widely in respect to the force required to turn them. Thus there is a constant danger to users of such doors as, for example, when a person stronger or heavier than the average applies his full force to a door which happens to be adjusted for easy rotation. Under such conditions, a pedestrian partly through the door may be struck by the advance of the wing or leaf behind him or a pedestrian about to enter from the opposite side may be caught between one of the leaves and the jamb an instant or so after the existence of an apparently ample margin of safety for entrance.

I have invented a novel means for temporarily checking the rotation of the revolving door at intervals during the course of a revolution thereof.

In a preferred embodiment, the invention comprises a pneumatic cylinder and piston mounted above the door and striker members for actuating it pivotally mounted on the wings or leaves of the door. A guide track engageable by the members as they approach the cylinder serves to cause them to travel for a short distance in a straight line while actuating the piston in the cylinder. This is permitted by the pivotal mounting of the members.

A complete understanding of the invention may be obtained from the following detailed description and explanation which refer to the accompanying drawings.

In the drawings,

Figure 1 is a horizontal section through a door having the invention applied thereto, taken on a plane just above the top of the door, along line 1—1 in Figure 2.

Figure 2 is a vertical section through the door jams showing the door in elevation.

Figure 3 is an enlarged horizontal section through the piston and cylinder constituting the pneumatic check.

Figure 4 is an elevation to enlarged scale showing one of the striker members.

Figure 5 is a view similar to Figure 1 showing a modification, and

Figure 6 is a view similar to Figure 4 showing

2

the form of striker member employed in the modified construction.

Referring now in detail to the drawings and, for the present, particularly to Figures 1 through 5, a revolving door 10 having four radial wings or leaves 11 is mounted for rotation on a vertical axis between arcuate jambs 12 in the known manner. A pneumatic check 13 comprising a cylinder 14, a piston 15 reciprocable therein and a piston rod 16 secured thereto and extending outwardly of the cylinder, is mounted above the door with the extremity of the piston rod projecting into the path of the wings or leaves 11, as shown. Preferably the check is recessed into the ceiling above the door opening defined by the jambs, as shown in Figure 2. A tension spring 17 on the piston rod normally urges the piston to its extreme left-hand position. The right-hand end of the cylinder has an outlet 18 therein controlled by an adjusting screw 19.

The wings or leaves 11 of the door are provided with striker members 20 adapted successively to engage the end of the piston rod 16 and force the piston 15 toward the right, thereby compressing air in the cylinder and serving momentarily to check the rotation of the door. Each member 20 includes a block 21 pivoted to the door on a horizontal hinge pin 22 and a cooperating yoke portion 23 pivoted thereto on a substantially vertical hinge pin 24. A striker tip or finger designated 25 extends upwardly from the yoke portion. A spring 26 normally tends to swing the lower portion of block 21 outwardly about the pin 22. The tip 25 normally bears on a circular track on the ceiling above the door (not shown), the block 21 being thereby forced into substantially vertical position against the pressure of spring 26.

A guide track in the form of an inverted channel is recessed into the ceiling above the door opening. The channel is straight for the greater portion of its length. The sides thereof flare outwardly at the entrance and as indicated at 28. The other or exit end of the channel designated 29 is disposed at an angle to the remainder thereof. The bottom of the channel slopes downwardly at both ends as indicated at 30 and 31. The outer side of the channel has a hole therein through which the end of the piston rod 16 extends, as shown in Figure 1.

The track 27 serves to deflect the striker tip 25 from the curved path it would normally traverse on a rotation of the door, into a path which is straight for a short distance, i. e., the stroke of the piston 15. Considering the rotation of

the door through an angle slightly greater than 90 degrees from the position in which it is illustrated, the tip 25 traverses the arc of a circle for about eighty degrees. It then enters the track 27 being guided thereinto by the flaring sides at the entrance end. The block 21, of course, swings outwardly at the bottom about pin 22 as the tip rides up the sloping bottom of the track at the entrance end indicated at 30. As the tip advances along the track, it is guided in a straight path and strikes the end of piston rod 16 with the result stated above i. e., the compression of air in the cylinder 14, and the momentary checking of the rotation of the door.

The character of the cushioning effect exerted by the piston and cylinder may be varied, of course, by adjusting the screw 19.

When the piston has been driven the full length of its stroke, the tip 25 enters the angularly disposed end portion 29 of the track and thus moves clear of the piston rod as the tip rides down the sloping end portion 31 of the track, the block 21 is restored to vertical position and spring 26 is compressed. The tilting of the finger necessary to conform to the path along the track 27 instead of to the arc of a circle, is permitted by the universal mounting afforded by the block 21 and yoke portion 23. After the striker tip or the finger has cleared the end of the piston rod, the latter with piston 15 is restored to normal extended position by spring 17, for engagement by the finger of the succeeding leaf and a repetition of the checking action.

It will be observed that the device described does not exert a constant drag on the door but only tends to arrest it slightly each time a leaf passes the air cylinder. Unless the door is given a particularly strong push, therefore, it will most probably stop at or just beyond the position of engagement with the piston rod. In this position, the door permits free entrance of the incoming pedestrian last to enter the door, yet affords the most effective closure against the weather out of doors.

The modification illustrated in Figures 5 and 6 is similar to that described above but is mounted on the ceiling above the door opening instead of being recessed thereinto. The door 32 has its leaves 33 notched or cut out as at 34 to clear the guide track 35 and pneumatic check 36. Striker members 37 pivoted to bases 38 on the leaves by vertical hinge pins 39 have upwardly extending striker fingers or tips 40 adapted to engage the end of piston rod 41 projecting from the cylinder 42 into the guide track. The fingers have springs 43 normally urging them outwardly, the interengaging portions of the fingers and their hinge bases being shaped to limit the extent of outward movement. The fingers thus swing inwardly in passing out of the exit end of the track but immediately snap outwardly under the force of the springs into position for easy entry into the track on the next approach thereto.

It will be evident from the foregoing that the invention provides a simple, inexpensive and effective means for checking the speed of a revolving door at intervals during each revolution, thereby guarding against the possibility that a person going through the door will be struck by the following leaf under the force exerted by the next incoming person, as well as the danger of pinching a person going in the opposite direction against the jamb as a result of sudden acceleration of the door.

Although I have illustrated and described but

a preferred embodiment and a modification of the invention, it should be understood that changes in the details of construction and arrangement disclosed may be made without departing from the spirit of the invention or the scope of the appended claims.

I claim:

1. Means for checking a revolving door having a plurality of radial leaves comprising a cylinder fixed above the door having a piston reciprocable therein with a piston rod secured thereto and extending outwardly from an end of the cylinder, fingers pivotally mounted on the leaves of said door adapted to engage said rod, and stationary guide means at the ceiling of the door opening adapted to confine said fingers to a rectilinear path on approaching said road.
2. A device as defined by claim 1 wherein said fingers are pivoted on substantially vertical axes.
3. A device as defined by claim 1 wherein universal mountings for said fingers are carried by said leaves.
4. A device as defined by claim 1 wherein said stationary guide means is an inverted channel.
5. A device as defined by claim 4 wherein said channel is substantially straight for the greater part of its length and has its exit end disposed at an angle to the remainder.
6. A device as claimed in claim 1 characterized by blocks pivoted on said leaves for tilting about horizontal axes, said fingers being pivoted on said blocks for swinging about substantially vertical axes.
7. A device as defined in claim 6 characterized by springs normally urging said blocks to tilt upwardly.
8. Means for checking a revolving door having a plurality of radial leaves comprising a finger mounted adjacent the top of each leaf, and projecting above the top thereof, an inverted channel recessed in the ceiling above the door opening and receiving said fingers upon rotation of the door, said channel having a rectilinear portion intermediate its ends, and a cylinder recessed in the ceiling above the door opening having a piston aligned with the rectilinear portion of the channel and normally extending therein to contact a finger on a door leaf upon rotation of the door.
9. Means for checking a revolving door having a plurality of radial leaves comprising a finger mounted adjacent the top of each leaf, an inverted channel fixed to the ceiling of the door opening and receiving said fingers on rotation of the door, said channel having a rectilinear portion intermediate its ends, a cylinder fixed to the ceiling of the door opening and having a piston in alignment with the rectilinear portion of the channel and normally extending thereon to contact a finger on a door leaf upon rotation of the door, and an opening in each door leaf adjacent the finger to permit passage of the channel and cylinder through the leaf on rotation of the door.
